UNITED STATES PATENT OFFICE

2,107,916

SHAPING FUR HEADS OF PELTS

Martin Tausz, Chicago, Ill.

Application January 24, 1936, Serial No. 60,745

9 Claims. (Cl. 35—20)

This invention relates to a device for shaping fur heads of pelts for fur coats and the like, and is more particularly concerned with devices of the class in which the fur pelt is left intact, and the head thereof is not severed from the rest of the pelt.

The object of the invention is to provide a head-forming device for properly shaping fur heads so as to make them substantially uniform and thus overcome the lack of uniformity when the shaping is performed manually as has heretofore been the custom, and to shape the head without severing the same from the rest of the pelt which of necessity requires sewing together and leaving unsightly seams.

The invention consists in the construction and combination of parts to be more fully described hereinafter and particularly set forth in the claims.

Reference is to be had to the accompanying drawings forming a part of this specification in which similar character references indicate corresponding parts in the various views, and in which

Fig. 1 is a plan view of my device in operative position;

Fig. 2 is a cross-section of the same taken on the lines 2—2 of Fig. 1 looking in the direction of the arrows;

Fig. 3 is a cross-section of the same taken on the lines 3—3 of Fig. 1 looking in the direction of the arrows;

Fig. 4 is a perspective view of the bottom metal member of my device; and

Fig. 5 is a similar view of the top metal member.

Fig. 6 is a plan view of the pelt covering the bottom metal member with the top metal member removed.

In the various figures, 1 represents the base or board on which the operation is performed; 2 a stop member on one side thereof; 3 screws for securely attaching the last mentioned member to the base; 4 an inclined side of said stop member; 5 the pelt; 6 the lower metal member;

7 the top metal member; 8 the perforations therein; 9 flanges or ears thereof; 10 a nut for a thumbscrew projecting through said ears; 11 the nose portion of the top metal member; 12 horizontal part of said top metal member; 13 the grooves of said member simulating the eyes of a pelt; 14 the inclined end of the bottom member; 15 the nose end of the pelt 5; 16 paper placed around the bottom metal member; 17 the flat front horizontal part of the bottom metal

member; 18 the vertical nose portion of the same; 19 the horizontal portion thereof; and 20 the openings in the ears 9 for cooperative action with the thumbscrew 10.

In the operation of the device the member 6, shown more particularly in Fig. 4, is inserted within the pelt 5, and said member is projected toward the head end of said pelt. In practice I prefer to place around said member, before covering the same with the pelt, paper having paste 10 on the top side thereof. This not only prevents the pelt from sticking to the member 6, but also tends to give rigidity to the fur head after it has been fashioned. While I prefer to use the paper, it is not indispensable to the operation of my invention. After the member 6 has been inserted within the fur pelt, the top member 7, more particularly shown in Fig. 5, is placed upon the pelt covered member 6. It will be observed that the nose portions 11 and 12 as well as the entire contour of said member 7 is shaped in a complementary manner to member 6. The two associated members with the pelt therebetween are then placed upon the base 1 with the head portion of said members projecting against the raised portion 4 of said base, and the associated parts are thereupon securely fastened together by means of the thumbscrews 10.

For the most efficient results the pelt should be moistened before the above operation is attempted, and the entire associated parts kept intact for such period as is necessary to dry the pelt, for the hastening of which the perforations 8 are provided.

By the use of my invention it will readily be seen that the heads of pelts will be substantially uniform, whereas at the present time by manually shaping the heads such uniformity is not possible, and obviously uniformity of heads is of great commercial and artistic desirability. As heretofore stated, this uniformity may be obtained without the use of paper, but the use thereof does tend to give rigidity and, accordingly, I prefer in practice to utilize the paper as indicated.

The figures as shown are directed towards a sable pelt, but it will be readily understood that the particular shaping of the members may be changed so as to simulate the heads of various animals whose pelt is involved. It will also be understood that the shaping members 6 and 7 may be either of metal or of other material.

What I claim as new and desire to secure by Letters Patent is:

1. A device of the class described for shaping

45

30

40

55

- a fur head of a circumferentially integral fur pelt, comprising a plate adapted to be removably inserted within the fur head of said pelt, said plate being of a shape to simulate the contour of the head of the animal represented by the pelt, a second plate complementary in contour to said first plate, a base for holding said members, and means for clamping said members securely to said base.
5. 2. In a device of the class described, a form adapted to receive removably an entire fur pelt and to shape the head thereof while it is drying, and comprising a rigid member simulating in form the contour of the head of the animal whose head is to be shaped and adapted to have said head placed thereon, a second rigid member complementary in shape to said first mentioned member adapted to serve as a covering to said head portion, means for securely interlocking the same with the first mentioned member and for securely attaching the same to a base on which said members rest.
10. 3. A device of the character described for shaping fur snouts and heads of uniform size, and comprising two complemental members simulating in shape the fur snout and head to be formed, and adapted to receive the fur pelt between said two members, an unmounted base, and means for securing said members to said base.
15. 4. A device of the character described for shaping snouts and heads of uniform size and comprising two complemental members simulating in shape the fur snout and head to be formed, and adapted to receive the fur pelt between said two members, an unmounted base having at one end thereof a projecting stop for contiguous contact with the snout portion of the fur, whereby uniformity of the shape of the snout portion is obtained, and means for securing said members to said base.
20. 5. A device of the character described, for shaping a fur pelt to simulate an animal's head, comprising a board having a stop member at one end thereof having an inclined side, a member whose contour delineates the snout and the head of the animal to be simulated, a complemental member for cooperative contact with said last mentioned member having ears on each side thereof with perforations therein, and a thumb screw
- adapted to pass therethrough for clamping the several members securely to the base.
6. A device of the character described, for shaping a fur head of a circumferentially integral fur pelt, comprising a plate adapted to be removably inserted within the head of said pelt, said plate being of a shape to simulate not only the contour of the snout of the animal represented by said pelt, but also the complete head thereof, a second plate complementary in contour to said first plate, and having flanges on each side thereof, having a hole in each flange, a thumb screw for insertion in said hole for securely associating said plates, and a base to which said plates are securely attached by means of said thumb screws, said plate having an inclined stop member for contacting and fashioning the end portions of the snout of the animal.
10. 7. A device of the character described, comprising a member simulating in contour the snout and head portion of an animal for insertion within the pelt of said animal, a second member complemental in contour to said first mentioned member, a base having at one end thereof a stop member and having therein thumb screws for securely fastening said members to each other and to said base.
15. 8. A device of the character described for shaping fur heads of uniform shape and contour, comprising a fashioning member shaped like an animal's snout and head, a second member complemental in shape to said first member, a base having a stop member against which the two said associated members rest contiguously, whereby the snout portion is in a predetermined form and slant when the fur pelt is positioned between said first two mentioned members, and means for associating said members and said base securely together.
20. 9. A device of the character described for shaping fur snouts and heads of uniform size and contour, comprising two separate members complemental in shape and simulating the snout and head of an animal, one of said members being floating and unattached, a base member, and means for securely associating said members together with the fur pelt contacting said floating member.
30. 40. 45. 50.
